UNITED STATES PATENT OFFICE.

THOMAS G. PLANT, OF BOSTON, MASSACHUSETTS, ASSIGNOR TO UNITED SHOE MACHINERY COMPANY, OF PATERSON, NEW JERSEY, A CORPORATION OF NEW JERSEY.

CONNECTION-CUTTER.

1,109,176.

Specification of Letters Patent.

Patented Sept. 1, 1914.

Application filed June 14, 1909. Serial No. 501,920.

To all whom it may concern:

Be it known that I, THOMAS G. PLANT, a citizen of the United States, residing in Boston, in the county of Suffolk and State 5 of Massachusetts, have invented an Improvement in Connection-Cutters, of which the following description, in connection with the accompanying drawings, is a specification, like letters on the drawings representing 10 like parts.

The invention to be herein described relates to boot and shoe machines, and more particularly to machines for truing up and leaving in proper shape the heel and shank 15 edges adjacent the heel breast, and commonly known as the heel connection.

When the breast of a heel is cut down, using a concave cutter, the varying width of the heel at the breast produces a curved 20 or irregular breast-line at the side edges of the heel, the irregular projecting edge being nearer the toe of the shoe at a point next the shank than at a point nearer the tread surface of the heel. It is also difficult to produce 25 a clean and uniformly cut line across the thickness of the shank to the top edge of the shank or to the crease, this usually being done by hand.

The aims and purposes of the present invention are to provide a machine intended 30 to finish the shoe along the edges of the heel and the shank edge adjacent thereto which will best be made clear by the following description and accompanying drawings 35 of one form or embodiment of means for carrying the invention into practical effect, it being understood that the invention is not circumscribed by the described and illustrated details, but is definitely pointed out 40 by the claims.

In the drawings: Figure 1 is a front view of a machine embodying the present invention, some of the parts being broken away; Fig. 2 is a side sectional view of Fig. 1 on 45 the line 2—2; Fig. 3 is an enlarged detail, parts being shown in section, to illustrate the relative position of the shoe, the breast gage, guillotine knife, and adjacent parts when the shoe is in operative position; Fig. 50 4 is a detail and detached view of the parts shown in the upper portion of Fig. 2, said parts being positioned for operation of the guillotine knife; Fig. 5 is a section on the line 5—5, to show more particularly the heel 55 rest support and its lever connection, some

of the parts being omitted for clearness of illustration; and Fig. 6 is a section on the line 6—6 of Fig. 1, some of the parts being broken away and others omitted for clearness.

The machine frame may comprise a supporting column 1 rising from a suitable base and having mounted on the top portion thereof a frame or head 2 to provide suitable supporting and bearing means for the 60 moving parts, as will hereinafter appear. Supported in suitable bearings on the machine head is a main driving shaft 3 having usual fast pulleys 4, 5 which may be actuated from any suitable source of power. 65

Inasmuch as the machine is designed to act upon the heel and shank edges at both sides of the shoe by similar means, the present embodiment of the invention contemplates a twin machine, that is, one part to 70 act upon one edge of a heel and shank at one side of the shoe, and the other duplicate part to act upon the other edge of the heel and shank. Fig. 1, therefore, shows such 75 duplicate or twin formation, and in describing the present embodiment of the invention one of the twin or duplicate parts will be referred to, it being understood that the other is a substantial duplicate.

Secured to the driving shaft 3 is a cam 85 6, Figs. 1 and 2, bearing upon which is a roll 7 carried by a knife actuator 8, Fig. 2, preferably formed as a lever pivoted on the stud 9 upon a suitably supporting bracket extending from the machine head and normally under the influence of a spring 10, one end of which is connected to the lever 8 at 11 and the other end to a pin 12 projecting from a part of the machine head. 90

Mounted in suitable ways 13, 13, Figs. 1 95 and 6, formed upon the machine head is the guillotine knife carrier 14 preferably braced by webs or flanges 15 and mounted to slide or reciprocate in the ways 13 on the machine head.

Pivottally connected to the knife carrier 14, as indicated in Fig. 2, is an arm 16 supported by a pin 17 projecting from the knife carrier 14 and extending through a slot 18 formed in the machine head 2. The arm 16 is under the influence of a spring 19, the end of which bears upon a pin 20 and which acts normally to depress the free end of the arm 16 into the path of the upper end of the actuator or lever 8, as will be apparent from 100 105 110

Fig. 2. In order to cause the described movement of the end of the arm 16 into the path of the actuator or lever 8, and thereby cause the guillotine knife carrier to be actuated, the following means is provided as 5 one form of this feature of the invention.

Pivotedly mounted at 21 to the heel rest carrier 22, Figs. 3 and 5, is a heel rest 23, preferably formed as a plate and having its 10 hub portion provided with a series of teeth 24, Fig. 3, adapted to engage the collars or teeth 25 on an adjusting screw 26 screw-threaded into the heel rest carrier 22 and provided with a milled head 27 whereby the 15 adjusting screw may be manipulated to change the angle of the heel rest in a manner as will be readily understood.

The heel rest carrier 22 is mounted to slide in suitable ways 28, Figs. 1 and 5, 20 formed on the machine head 2, and is adjustably connected by a slot 29 and adjusting bolt 30 to an arm 31 pivoted at 32 to a link 33 jointed at 34 to the upper end 25 of a lever 35 fulcrumed on the stud 9. The lever 35, thus or otherwise connected to the heel rest 23, is normally maintained in position with the heel rest projecting well to the front or toward the operator by a spring 36, Fig. 5, one end of which is connected at 37 to the said lever 35 and the other end 30 to a fixed point on the machine head.

It will be evident from the construction described that, if a heel 8 be placed against the heel rest 23 and forced backward, the 35 heel rest will give and enable the shoe to be positioned in a manner as will presently appear. It is expedient at this time to refer to the means for operating the guillotine knife and as one embodiment of means 40 to this end attention is directed to Figs. 1, 2 and 4.

Mounted in suitable bearings 38, Fig. 1, 45 formed in the machine head is a rock shaft 39 having secured thereto the hub 40 of a depending pin 41, Fig. 6, on which is mounted the sleeve 42 provided with the shank knife carrier or arm 43, to the end of which is secured in suitable manner the shank edge cutting knife 44. This knife, see Figs. 50 1, 2, 4 and 6, is preferably carried in suitable ways 45 formed in a knife head 46, said knife 44 being clamped in adjusted position by a set screw 47. Extending in proximity to the knife edge is a guard 48 55 properly secured to the head, as at 49. The lower end of the pin 41 is provided with a nut 50, Fig. 6, for confining the sleeve 42 in place on said pin.

From the construction described it will 60 be apparent that the shank knife carrier or arm 43 may be turned about the rock shaft 39 as a center and is normally held in depressed position by means of a spring 51, Fig. 6, secured at 52 to a projection 53 65 extending from said sleeve and having its

other end 54 connected to the upper portion of an adjusting screw 55 which is passed through a bracket or lug 56 extending from the machine frame, said adjusting screw being provided with a nut 57 below the bracket 70 to properly adjust the tension of the spring 51. To limit the action of the spring, the bearing 38, Figs. 1 and 6, is provided with a stop 58 which is adapted to be engaged by a coacting stop 59 formed on the hub portion 40 of the pin 41. To limit the upward movement of the shank knife carrier or arm 43 the hub of the pin 41 is provided with another stop 60 adapted to engage a stop 61 secured to the bearing 38 or other stationary part, the construction being such that under the action of the spring 51 the shank knife carrier or arm 43 will be normally held in the position indicated in Fig. 6, that is, depressed, with the stops 58 and 59 in engagement, and that it may be forced upward or turned about the rock shaft 39 as a center to the limit defined by the stops 60 and 61.

Secured to the rock shaft 39 at the end 90 thereof is an arm 62, Figs. 1, 2 and 4, having a pin 63 engaging a slot 64 in an arm 65 pivoted at 66 to the machine head 2 and having at its outer end the dog 67 pivotally connected thereto. The dog 67 is 95 provided near its lower portion with an angular slot 68 which is engaged by a pin 69 projecting from the arm 70 of a lever pivoted at 71 to the machine head, said lever being normally under the influence of a 100 spring 72 disposed between the arm 73 of said lever and the dog 67, the construction being such that the dog 67 is normally influenced to swing contra-clockwise about its pivotal connection with the arm 65, and 105 the lever carrying the pin 69 is normally influenced to force the pin 69 downward. The arm 110 16 pivotally mounted at 17 to the guillotine knife carrier slide 14 has a shouldered portion 74 adapted to engage with the pin 69 or the end of the arm 70, whereby said arm 16 may be held in the position indicated in Fig. 2 with the end of said arm out of the path of movement of the actuator or lever 8.

A shoe being placed with its heel upon the heel rest 23, and said heel rest being forced backward, as hereinbefore described, to bring the shank portion of the shoe below the shank cutting knife 44, and then the shoe being moved so as to raise the shank knife carrier or arm 43, it will be noted that the rock shaft 39 will be turned to an extent limited by the stops 60 and 61, and that the dog 67 will likewise be raised to 125 disengage the pin 69 or the end of the arm 70 from the shoulder 74 of the arm 16, whereupon said arm 16 will drop with its end in position, Fig. 4, to engage the actuator or lever 8, so that as the actuator or 130

lever 8 moves to the left, Fig. 4, it will correspondingly move the arm 16 and likewise the guillotine knife carrier 14 and the guillotine knife 75 to cut along the heel breast line 76, Fig. 3, and remove therefrom any projecting or uneven portion of the heel at this point.

In order to retract the guillotine knife carrier and knife there is connected to the 10 knife carrier at one end a spring 77, Figs. 2 and 6, the other end of said spring being connected at 78 to a stud or other stationary part connected to the machine head. The arm 16 at its free end carries a pin 79 which, 15 when said arm is moved by the actuator or lever 8 in the manner hereinbefore stated, contacts with the lower end of the dog 67 and moves it so as to position the pin 69 on the lever arm 70 in the downturned portion 20 of the slot 68, whereupon the spring 72 throws the pin 69 to the lower part of said slot. As the knife carrier returns to initial position, the end of the arm 70 or pin 69, being now in the lower part of the slot 68, 25 contacts with the shoulder 74 on the arm 16 and raises the end of said arm out of the path of movement of the actuator or lever 8. The pin 69 remains in the lower part of the slot 68 until the shank knife carrier or 30 arm 43 is lowered by movement of the shoe, which causes a like movement of the dog 67 to position the pin 69 opposite the upper part of the slot, whereupon the spring 72 throws the lower end of the dog 67 to the 35 right, Fig. 2, and the parts assume the relation indicated in Fig. 2. It will be noted from the construction described that after the guillotine knife has made one excursion and return the end of the arm 16 will be 40 thrown out of the path of the actuator or lever 8, regardless whether the shank knife carrier or arm 43 is held raised or not. that after making one cut, the guillotine knife 75 returns to initial position and re- 45 mains inoperative or inactive. The guillotine knife 75 is preferably connected to the carrier 14, as indicated in Fig. 3, that is, the guillotine knife is supported in ways 50 on the carrier and its rear end 81 bears against the head of an adjusting screw 82, whereby the knife may be adjusted in position as circumstances make desirable. In order that the heel S of the shoe may be properly positioned on the heel rest it is 55 desirable to employ a breast gage 83, as indicated in Figs. 1 and 3. The breast gage 83 is adjustably supported by means of a threaded stem 84, Figs. 1, 2 and 6, by an upright arm 85 clamped and splined upon 60 the shaft 86, as will be clear from Figs. 2 and 6. The breast gage 83 may be likewise adjusted horizontally by means of the screw-threaded stem 87 and nut 88, Figs. 1, 2 and 3. 65 It is desirable to remove the breast gage

from its position, as indicated in Fig. 3, when the guillotine knife 75 moves forward to perform its work, and to this end the guillotine knife carrier 14, Fig. 6, has a lower inclined or cam portion 89 adapted to 70 contact with a roll or projection 90 carried by an arm 91 pivoted at 92, Fig. 1, to the head 2 of the machine frame, the projecting end 93 of said arm being normally under the influence of a spring 94 connected thereto and at a point 95 to the machine head, Fig. 1, the construction being such that the arm 91 will normally be maintained in the position indicated in Fig. 1. The arm 91 is provided with an inclined slot 96, Fig. 1, 75 so which is engaged by a pin 97 projecting from an arm 98, Figs. 2 and 6, secured to the shaft 86, the construction being such that, upon forward movement of the guillotine knife carrier 14, the inclined or cam 80 portion 89 thereof will contact with the roll or projection 90 carried by the arm 91 and depress the slotted end of said arm, thereby, through the arm 98, turning the shaft 86 and moving the breast gage 83 out of the 85 path of movement of the guillotine knife 75. The edge of the heel having thus been trimmed by the guillotine knife, and said knife having returned to its initial position, as hereinbefore pointed out, it is desirable 90 to trim the edge 99 of the shank portion in front of the heel, Fig. 3. As one means to this end there is mounted on the main shaft 3 a disk 100, Figs. 1, 2 and 6, one face of 95 said disk being provided with a series of cam projections 101, Fig. 1. Pivottally mounted at 102 on the sleeve 42 carrying the shank knife carrier or arm 43 is a vibrator arm 103, the purpose of which is to vibrate the shank cutting knife 44 and cause 100 it to remove the edge 99, Fig. 3, from the shank of the shoe sole. Mounted on the end of the vibrator arm 103 is a roll 104 adapted to bear upon the cam portions 101 of the disk 100 when said roll 104 is depressed into position for such engagement, as will presently 105 appear. Connected to the vibrator arm 103 is a spring 105, Figs. 1 and 6, which normally acts to hold the roll 104 against the face of the disk 100. 110

Pivottally connected at 106 to the vibrator arm 103 is a treadle rod 107, Figs. 2 and 6, pivottally connected at 108 to an arm 109 fixed to a shaft 110 mounted in suitable bearings on the machine frame. Projecting 115 from the shaft 110 is an arm 111 connected at 112 to a treadle rod 113, whereby upon depression of the treadle rod by the treadle 114 the shaft 110 may be turned in its bearings and the rod 107 pulled downward to 120 force the roll 104 of the vibrator arm 103 into the path of movement of the cam projections 101 on the disk 100, the construction being such that as the main shaft rotates, with the parts in the position indicated, the 125 130

shank cutting knife 44 will be vibrated in a direction longitudinally of the shoe shank. As hereinbefore pointed out, the guillotine knife makes one cutting excursion and returns to initial position and then stops, regardless of whether the shank knife carrier or arm 43 is still held in raised position by the shoe or not, but, should the shank knife carrier or arm 43 be lowered and then raised, the guillotine knife would again start on its excursion and probably interfere with the operation of cutting the edge of the shank portion of the shoe or do other damage. The present invention, therefore, contemplates means operative upon giving to the shank knife 44 its vibrating cutting action to lock or hold the shank knife carrier or arm 43 in its raised position and consequently prevent actuation of the guillotine knife. As one means of carrying this feature of the invention into effect, the hub portion of the vibratory arm 103 is provided with a recess 115, shown by dotted lines in Fig. 6, and the sleeve 42 is provided 25 with a pin 116 engaging said slot 115, the construction being such that upon depression of the rod 107, as hereinbefore pointed out, the vibrating arm would be turned about its pivotal support 102 as a center and bring 30 the wall of the slot 115 at the left of the pin 116 into contact with said pin, thereby holding the sleeve 42 and consequently the shank knife carrier or arm 43 in the position indicated in Fig. 6, that is, with the shank knife 35 carrier in the raised position to which it was originally forced by contact with the shoe. Upon depression of the treadle 114 to cause vibration of the shank cutting knife 44 it is desirable that the heel rest 23 and 40 the breast gage 83 be moved from their position, as indicated in Fig. 3, so that the shoe may be freely turned or manipulated by the operator. To this end the lever 35, Fig. 5, has a depending toe portion 117, Figs. 2 and 45 5, which is in the path of movement of an adjusting screw 118 carried in the end of an arm 119 mounted on the shaft 110 and consequently movable with said shaft upon depression of the treadle rod 113, the construction 50 being such that upon depression of the treadle the lever 35 will be moved to the right, Fig. 5, and consequently withdraw the heel rest 23. The arm 109, Fig. 2, has passing through a perforation in the end thereof 55 a rod 120 having disposed between the nut 121 threaded to its lower end and the end of the arm 109 a spring 122, said rod extending upward and provided with a slotted end portion 123 which engages a pin 124 projecting from the arm 91, the construction being 60 such that upon depression of the treadle 114 and consequent downward movement of the arm 109, Fig. 2, the rod 120 will be depressed, thereby depressing the arm 91 and 65 causing its slot 96 to act upon the pin 97 and

cause rotative movement of the shaft 86 and consequent movement of the breast gage 83 away from operative position.

From the construction described as one embodiment of the present invention it will 70 be apparent that the edge of the heel extending from the tread portion thereof to the shank at the breast line will be first trimmed by a clean reciprocating cut of the guillotine knife, said knife being started into actuation 75 by movement of the shoe into operative position; and subsequently thereto the shank cutting knife is caused to act upon the shank edge in front of the heel breast by a vibratory cutting action, the guillotine knife being held and locked out of possible operation during the action of the shank cutting knife.

Various changes may be made in the details of structure, and the arrangement and disposition of parts may be variously modified within the true scope of the present invention which is definitely pointed out by the claims.

What is claimed is:

1. In a machine of the character described, the combination of a knife for cutting the edge of a heel breast, a knife for cutting the edge of the shank in front of the heel breast, and means for causing said knives to act 95 successively.

2. In a machine of the character described, the combination of a heel rest for supporting the tread surface of a heel, a knife for cutting the edge of a heel breast, a knife for cutting the edge of the shank in front of the heel breast, and means for causing said knives to act successively.

3. In a machine of the character described, the combination of a heel breast gage, a knife for cutting the edge of a heel breast, a knife for cutting the edge of the shank in front of the heel breast, and means for causing said knives to act successively.

4. In a machine of the character described, the combination of a heel breast gage, a knife for cutting the edge of a heel breast, a knife for cutting the edge of the shank in front of the heel breast, means for causing said knives to act successively, and means 115 for moving the breast gage away from the heel during the action of the heel edge knife.

5. In a connection cutter, the combination of a heel rest for supporting the tread surface of the heel, a heel breast gage, said heel rest and breast gage acting to position the heel for treatment, and a cutter for acting 120 on the edge of the shank in front of the heel breast.

6. In a connection cutter, the combination of a heel rest for supporting the tread surface of the heel, a heel breast gage, said heel rest and breast gage acting to position the heel for treatment, a cutter for acting on the edge of the shank in front of the heel breast,

- and means for moving the heel rest and breast gage out of position during the action of said cutter.
7. In a connection cutter, the combination of a cutter for acting on the edge of the heel breast, a cutter for acting on the shank in front of the heel breast, and means operative on movement of the last named cutter to actuate the first named cutter.
- 10 8. In a connection cutter, the combination of a heel rest to engage the tread surface of a heel, a cutter for acting on the edge of the heel breast, a cutter for acting on the shank in front of the heel breast, and means operative on movement of the last named cutter to actuate the first named cutter.
- 15 9. In a connection cutter, the combination of a heel rest to engage the tread surface of a heel, a breast gage to engage the breast of a heel positioned on the heel rest, a cutter for acting on the edge of the heel breast, a cutter for acting on the shank in front of the heel breast, and means operative on movement of the last named cutter to actuate the first named cutter.
- 20 10. In a connection cutter, the combination of a heel rest to engage the tread surface of a heel, a breast gage to engage the breast of a heel positioned on the heel rest, a cutter for acting on the edge of the heel breast, a cutter for acting on the shank in front of the heel breast, means operative on movement of the last named cutter to actuate the first named cutter, and means to move the breast gage out of position during the action of the heel edge cutter.
- 25 11. In a connection cutter, the combination of a heel rest to engage the tread surface of a heel, a breast gage to engage the breast of a heel positioned on the heel rest, a cutter for acting on the edge of the heel breast, a cutter for acting on the shank in front of the heel breast, means operative on movement of the last named cutter to actuate the first named cutter, and means to move the heel rest and breast gage out of position during the action of the shank cutter.
- 30 12. In a heel connection cutter, the combination of a cutter for acting on the breast edge of a heel, means for reciprocating said cutter, a cutter for acting on the shank in front of the heel breast, and means for vibrating said last named cutter.
- 35 13. In a heel connection cutter, the combination of a heel edge cutter for acting on the edge of the heel breast, a shank cutter for acting on the shank edge in front of the heel breast, and means controlled by movement of the shank cutter into operative relation with the shank of the shoe for operating the heel edge cutter.
- 40 14. In a machine of the character described, the combination of a knife for cutting the edge of a heel breast, a knife for cutting the edge of the shank in front of the
- heel breast, means for causing said knives to act successively, and a lock to insure the inoperativeness of one cutter while the other cutter is acting.
- 45 15. In a connection cutter for boots and shoes, the combination of a heel edge cutter to act upon the edge of the heel breast, a shank cutter to act upon the shank of a shoe in front of the heel breast, said shank cutter being movable by the shoe as it is positioned in the machine, and means controlled by such movement of the shank cutter to cause the heel edge cutter to make one cut and then be brought to rest.
- 50 16. In a connection cutter for boots and shoes, the combination of a heel edge cutter to act upon the edge of the heel breast, a breast gage to engage the heel breast, and means operating in advance of the cutting action to move the breast gage out of position during the action of the heel edge cutter.
- 55 17. In a connection cutter for boots and shoes, the combination of a heel rest against which the tread surface of a heel may be held after the heel has been attached to the shoe, a heel edge cutter to act upon the edge of the heel breast, a breast gage to engage the heel breast and means operated by the heel edge cutter to move the breast gage out of position during the action of the heel edge cutter.
- 60 18. In a connection cutter, the combination of a heel edge cutter to act upon the edge of the heel breast, a shank cutter to act upon the shank in front of the heel breast, and a yielding heel rest movable by pressure of the heel thereon to position the shank of the shoe with respect to the shank cutter.
- 65 19. In a connection cutter, the combination of a heel edge cutter to act upon the edge of the heel breast, a shank cutter to act upon the shank in front of the heel breast, a yielding heel rest movable by pressure of the heel thereon to position the shank of the shoe with respect to the shank cutter, said shank cutter being movable by the shoe, and means controlled by such shoe-impelled movement of the shank cutter to cause actuation of the heel edge cutter.
- 70 20. In a connection cutter, the combination of a shank cutter to act upon the shank of a shoe in front of the heel breast, means controlled by the operator for vibrating said shank cutter, a heel rest, and devices for moving said heel rest from position by actuation of said operator-controlled means.
- 75 21. In a connection cutter, the combination of a shank cutter to act upon the shank of a shoe in front of the heel breast, means controlled by the operator for vibrating said shank cutter, a heel rest, a breast gage, and devices for moving the heel rest and breast gage from position upon actuation of the said operator-controlled means.

22. In a connection cutter, the combination of a heel edge cutter for acting upon the edge of the heel breast, a shank cutter for acting on the shank of a shoe in front of the heel breast, means controlled by work-induced movement of the shank cutter to cause the heel edge cutter to be operated for one cut and then be brought to rest, operator-controlled means for actuating the shank cutter, and a lock for holding the shank cutter in work-induced position during the actuation of said shank cutter.

23. In a connection cutter for boots and shoes, the combination of a heel edge cutter to act upon the edge portions of a heel breast, a movable heel rest against which the tread surface of a heel may be placed, a heel breast gage to engage the heel breast, means controlled by movement of the heel into position for operating the heel edge cutter, and means for moving the breast gage out of position during the action of said cutter.

24. In a connection cutter for boots and shoes, the combination of a heel edge cutter to act upon the edge portions of a heel breast, a shank cutter to act upon the shank of a shoe in front of the heel breast, means controlled by movement of the shank cutter for causing the heel edge cutter to act, and a lock to prevent simultaneous action by both cutters.

25. In a connection cutter for boots and shoes, the combination of a heel edge cutter to act upon the edge portions of a heel breast, a shank cutter to act upon the shank of a shoe in front of the heel breast, means controlled by work induced movement to cause the heel edge cutter to operate, and treadle-controlled means for causing operation of the shank cutter.

26. In a connection cutter for boots and shoes, the combination of a heel edge cutter to act upon the edge portions of a heel breast, a shank cutter to act upon the shank of a shoe in front of the heel breast, means controlled by work induced movement to cause the heel edge cutter to operate, treadle-controlled means for causing operation of

the shank cutter, and means to prevent concurrent cutting action by the two cutters.

27. In a machine for acting upon the bottoms of boots and shoes, the combination of a cutter to act along the shank, a second cutter acting at an angle to the first-named cutter to cut into the shank, and means controlled by movement of the work for starting one of said cutters into operation.

28. In a machine for acting upon the bottoms of boots and shoes, the combination of a cutter to act along the shank, a second cutter acting at an angle to the first-named cutter to cut into the shank, means controlled by movement of the work for starting one of said cutters into operation, and separate means for actuating the other cutter.

29. In a machine for acting upon the bottoms of boots and shoes, the combination of a cutter to act along the shank, a second cutter acting to cut into the shank, and means for operating one of said cutters, said means comprising a rotary element having projections, an arm connected to said cutter, and means for moving the arm into the path of said projections.

30. In a machine for acting on boots and shoes, the combination of a cutter to trim the edge of the heel breast, a second cutter to trim the edge of the shank in front of the heel breast, and means for actuating said cutters to cause them to act successively in intersecting paths.

31. In a machine for acting on boots and shoes, the combination of a cutter to trim the edge of the heel breast, a second cutter to trim the edge of the shank in front of the heel breast, means for positioning a heel for the action of the cutters, and means for actuating said cutters to cause them to act successively in intersecting paths.

In testimony whereof, I have signed my name to this specification, in the presence of two subscribing witnesses.

THOMAS G. PLANT.
